US00D680521S

(12) **United States Design Patent**
Fathollahi

(10) **Patent No.:** **US D680,521 S0**
(45) **Date of Patent:** **** Apr. 23, 2013**

(54) **CASE**

(75) Inventor: **Andy Fathollahi**, Irvine, CA (US)

(73) Assignee: **Incipio Technologies, Inc.**, Irvine, CA (US)

4,551,379 A 11/1985 Kerr
D287,905 S 1/1987 Oyamada
4,845,863 A 7/1989 Yung-Mao
4,911,671 A 3/1990 Rogers
D315,634 S 3/1991 Yung-Mao
D317,255 S 6/1991 Turk

(Continued)

(**) Term: **14 Years**

(21) Appl. No.: **29/408,873**

(22) Filed: **Dec. 16, 2011**

FOREIGN PATENT DOCUMENTS

FIG. 1 is a top end view of a case;

FIG. 2 is a bottom end view thereof;

FIG. 3 is a left side view thereof;

FIG. 4 is a right side view thereof;

FIG. 5 is a front view thereof;

FIG. 6 is a back view thereof; and,

FIG. 7 is a back perspective view thereof.

The illustrated broken lines are for illustrative purposes only and form no part of the claimed design. The broken lines showing dot dash configuration constitute an unclaimed boundary of the claimed design.

1 Claim, 5 Drawing Sheets
